UNITED STATES PATENT OFFICE.

JAFEW S. VAN BUREN, OF ALBANY, NEW YORK.

DESIGN FOR A HEATING-STOVE.

SPECIFICATION forming part of Design No. 23,013, dated January 23, 1894.

Application filed September 16, 1893. Serial No. 485,724. Term of patent 3½ years.

To all whom it may concern:

Be it known that I, JAFEW S. VAN BUREN, of Albany, in the county of Albany and State of New York, have invented certain new and useful Improvements in Designs for Stoves; and I do hereby declare the following to be a full, clear, and exact description of the invention, such as will enable others skilled in the art to which it pertains to make and use it, reference being had to the accompanying drawing, which forms part of this specification.

My invention relates to improvements in designs for stoves, of which the following is a full description.

The accompanying drawing represents a perspective view of a stove which embodies my design.

The essential features of my design consist of the base A, provided with ornamentation to be particularly described farther on, the ash pit B having at its sides the outwardly supported leaf-like arms or wings C connected at their upper ends by bars D. Above this ash pit is an ornamented rectangular portion E forming the fire-port, and above this the rectangular ornamented portion F which forms the combustion chamber having at its corners the representations of pillars G, which are connected by the ornamented arches H, the two ornamented portions E and F forming the body of the stove. This rectangular portion F is surmounted by the ornamented tops I and J.

The particular design of the base consists of the convolutes K near the corners thereof; the convolutes J at the center thereof, and the scrolls M which connect the convolutes K and L; and the ornamented legs s, depending between the corner convolutes K.

The particular design of the front of the stove consists of the combined register and door a, above this the open scrollwork b having at its center the circle c, which incloses the representation t, of an acorn. Above this the front has at its corners the pillars G before mentioned, the door f between them, the arched panel H before mentioned connecting

the upper ends of the pillars, and the open work g, and the parallel beads e, forming together a horizontal division between and connecting the portion having the door f, and the portion E carrying the representation of an acorn, and this portion E has its corners ornamented by a leaf-like figure d.

The sides of the stove consists in the particular design, of the ornamented portion B having the wings C with a leaf-like ornamentation which extends down and slightly upon the base, the upper ends of these wings being connected by the bar D, both of which have been mentioned hereinbefore. Above this is a portion E ornamented with open work like the corresponding portion of the front of the stove, and above this the open scroll work F, surmounted by the radial openings i, forming an arch-like appearance over the said scroll work F. At the sides of the portions F and E are respectively the pillars G and leaf ornamentation d named in connection with the description of the front of the stove. The series of beads e mentioned in the description of the front of the stove, also separate the portions E and F and form a horizontal bead between them.

Having thus described my design, what I claim, and desire to secure by Letters Patent, is—

1. The design for a stove substantially as herein shown and described.
2. In the design for a stove the base thereof substantially as herein shown and described.
3. In the design for a stove, the body thereof substantially as herein shown and described.
4. In the design for a stove the top thereof substantially as herein shown and described.

In testimony whereof I affix my signature in presence of two witnesses.

JAFEW S. VAN BUREN.
